UNITED STATES PATENT OFFICE.

FREDERICK KOHLRUSS, OF BALGONIE, SASKATCHEWAN, CANADA.

STOOKER.

1,328,674.

Specification of Letters Patent. Patented Jan. 20, 1920.

Application filed July 22, 1918. Serial No. 246,113.

To all whom it may concern:

Be it known that I, FREDERICK KOHLRUSS, of the town of Balgonie, in the Province of Saskatchewan, Canada, have invented certain new and useful Improvements in Stookers, of which the following is the specification.

My invention relates to improvements in stookers and the object of the invention is to devise a simple and efficient form of stooker which may be easily operated to form a stook and deposit the same upon the ground so that there will be no danger of the stocks being upset after being set up by the forward travel of the machine and it consists essentially of the following arrangement and construction of parts as herein-after more particularly explained.

Figure 1, is a general perspective view of my device.

Fig. 2, is a longitudinal section through Fig. 1.

Fig. 3, is a plan view.

Fig. 4, is a detail view of the catch number used in connection with my device.

In the drawings like characters of reference indicate corresponding parts in the various figures.

1 indicates the main frame comprising the side bars 1^x and 1' connected together at one end by the frame end portion 1² and in proximity to the same end by a cross bar 1³. 1⁴ indicates a supplemental frame supported in the main frame and extending rearwardly from the cross bar 1³ and connected directly to the side bar 1^x and to the side bar 1' by a cross bar 1⁵. The opposite end of the frame is open as will be clearly seen from the drawing.

2 indicates the main shaft upon which is supported the gear 2^x and sprocket gears 2' and 2². 3 indicates the main wheel mounted upon a short shaft 3^x supported by the side bar 1^x and longitudinal bars 1⁶ of the supplemental frame. 3' indicates a sprocket gear mounted upon the shaft 3^x and connected by a sprocket chain 3² to the sprocket gear 3¹⁰ mounted upon the shaft 3⁷ upon which is secured a pinion 2⁰ meshing with the pinion 2^x. 3³ indicates a sprocket gear mounted upon a short shaft 3⁰ carried by the bars 1⁶ and 1⁷ and 3⁴ indicates a sprocket pinion also mounted upon the shaft 3⁰ adjacent to the sprocket wheel 3³ and revolving in unison therewith. 3⁵ indicates a sprocket chain connecting the sprocket chain 3³ with

the sprocket gear 2' mounted upon the shaft 2. 4 indicates a stud shaft carried by the longitudinal bar 1⁷ of the supplemental frame 1⁴. 4^x indicates a mutilated sprocket gear mounted upon the stud shaft 4 in a line and designed to mesh with the sprocket pinion 3⁴. Normally the sprocket pinion 3⁴ is located in a mutilated portion 4' of the sprocket gear 4^x.

5 and 6 indicate frame standards carried by the supplemental frame 1⁴ at each side thereof, each being provided with upwardly extending standard portions 5^x and 6^x. 7 indicates a rocking shaft journaled in the standard portions 5^x and 6^x. 8 indicates a sheaf receiving plate which is preferably concaved crosswise and provided with slotted openings 8^x and 8'. 8² indicates a lug depending from the lower face of the plate 8 in proximity to one end thereof and provided with a sleeve end 8³ secured to the rocking shaft 7. 9 indicates a link hingedly connected at 9^x to the rear end of the plate 8, the opposite end being pivotally connected at 9' to the mutilated gear 4^x.

10 indicates a U-bracket carried by the standard frame 6. 11 indicates a longitudinally movable rod slidably held in the arms of the U-bracket 10 and provided with a stationary collar 11^x and a surrounding compression spring 11' extending between the collar and the rear arm of the U-bracket 10. The orifice of the U-bracket through which the forward end of the rod 11 passes is elongated vertically so as to allow of a slight vertical movement of the rod 11 for a purpose which will hereinafter appear.

The forward end of the rod 11 is downturned at 11⁰. 12 indicates a sheaf receiving plate located over the central portion of the sheaf receiver 8 and provided with upwardly extending spicular projections 12^x and at its rear end with a down-turned arm 12' extending through the slotted orifice 8^x of the sheaf receiver 8. The lower end of the arm 12' is connected by a tension spring 12² to the lower face of the sheaf receiver 8, such spring extending forwardly in an upwardly inclined direction. The opposite end of the plate 12 is provided with a depending lug 12². 12³ indicates a link pivotally connected to the lug 12² at its upper end and provided at its lower end with an eye 12⁴ through which the rod 11 freely passes, the link 12³ being connected to the rod 11 in proximity to its forward end.

The opposite end of the rod 11 is provided with a head 11² provided with a depending tooth projection 11³ adapted to engage the teeth of the sprocket 4^x.

5 It will be noticed particularly on referring to Fig. 3 that the rod 11 is located directly over the sprocket chain 3⁵ and that, therefore, when the forward end of the rod 11 is depressed the down-turned portion 11⁰ 10 thereof will engage with the links of the sprocket. The sprocket gear 2² mounted upon the shaft 2 is provided with a clutch member 2³ formed integral therewith.

It will be noticed that the gear 2² is freely 15 mounted upon the shaft 2 and 2⁴ indicates a clutch member which is feathered on to the shaft 2 and provided with an annular groove 2⁵.

13 indicates a clutch operating lever pivoted at 13^x and provided with a fork 13' engaging the annular groove 2⁵ of the clutch member 2⁴. The operating end of the lever is connected by a tension spring 14⁰ to a bracket 14⁶ mounted in a stationary position upon the main frame. 15⁰ indicates a cord or other operating means extending from the lever 13 to a suitable operating device located adjacent to the driver's seat upon the binder. 14 indicates the shock former into which the sheaves are delivered from the sheaf receiver 8. 15 indicates a tilting frame supported between the side bars 1^x and 1' of the main frame by trunnion members 15^x and 15'. The trunnion member 15' is provided with a crank end 15² for a purpose which will hereinafter appear.

16 indicate link members swung at their lower end upon the front bar of the rocking frame 15 and pivotally connected at their 40 opposite end at 16^x to the forward portion of the lower portion of the shock former. By this means the front end of the shock former is supported. In order to support the rear end of the shock former I provide a swinging frame 17 provided with trunnions 17^x and 17' also mounted upon the side bars 1^x and 1' of the main frame. The trunnion 17' is also provided with a crank portion 17².

It will be noted that the rear end of the 50 swinging frame 17 is open and that the ends of the side arms of the frame are provided with outwardly projecting portions 17².

14^x indicates a bearing member carried by the lower portion of the shock former 14 in 55 proximity to its rear end and through which the front bar of the rocking frame 17 extends and is turnably held. The shock former 14 is divided into three portions, the lower portion 14' being substantially semi-circular in cross section and of semi-conical form. To each edge of the portion 14' are hingedly connected arc-shaped flaps 14² and 14³. 14⁴ indicates a tension spring connecting the flaps 14² and 14³ to the sides of the lower portion 14' of the shock former there-

by normally holding the portions 14² and 14³ in their open position. 14⁵ indicate links hingedly connected at their inner ends to the inner edges of the flaps 14² and 14³. 15³ indicate levers swingably mounted upon the 70 side portions of the lower portion 14' of the shock former. 15⁴ indicates a ball and socket connection between the rearwardly extending arm 15⁵ of each of the levers 15³ and a corresponding link 14⁶. The arm 15⁵ of each lever 15³ is also connected by a tension spring 15⁶ to the shock former so as to have a downward draw upon the arm 15⁵. The opposite arms 15⁷ of the levers 15³ are connected together by a looped cable 15⁸.

80 18 indicates a pulley mounted upon a suitable member 18^x carried by the main frame. 18' indicates a cable connected at one end to the central portion of the looped cable 15⁸ and at the opposite end to a tension spring 85 18² connected to a cross bar 18³ carried by the main frame.

In order to support the butt end of the shock when in position in the shock former and during the formation of a shock I have 90 provided the following device.

95 19 indicate brackets extending outwardly from each side of the main frame in proximity to its rear end. 19' and 19² indicate standards supported at their lower ends upon the brackets 19 and extending upwardly at each side of the rear end of the shock former 14. The upper ends of the standard bars 19' and 19² are inturned and provided with bearing ends 19³ and 19⁴. 19⁵ indicates a U-shaped frame, the vertical arms of which are provided at their outer ends with out-turned trunnion portions 19⁶ and 19⁷ swingably mounted in the bearing ends 19³ and 19⁴. The lower bar of the frame 19⁵ is provided with lateral projections 19⁸ for a purpose which will hereinafter appear. The U-shaped frame 19⁵ is provided with a filling of suitable material 19⁹. The rear ends of the side bars 1^x and 1' of the main frame are 110 provided with jaws X and X'.

115 20 indicate swinging catches pivotally mounted in the jaws X and X'. The upwardly extending teeth 20^x of the catches engage the projections 19⁸ of the frame 19 so as to lock it in its inward position against the rear end of the shock former 14. The catches 20 are provided with rearward extensions 21 which normally rest upon the lateral projections 17² of the swinging frame 120 17. The catches 20 are connected by tension springs 22 to depending brackets 23 carried by the main frame. The trunnion portion 19⁷ is provided at its outer end with a crank portion 19¹⁰. 24 indicates a short shaft journaled in suitable bearings 25 carried by the side 1' of the main frame. 26 indicates a sprocket gear mounted upon the inner end of the shaft 24. 26^x indicates a sprocket chain connecting the sprocket 26 with the sprocket 130

gear 2². 27 indicates a link pivotally connected at one end to the sprocket gear 26 and at the opposite end to the rear cross bar of the swinging frame 15. 27⁰ indicates a crank 5 wheel mounted upon the outer end of the shaft 24 and connected by a link 28 to the crank end 17² of the trunnion 17¹. 29 indicates a link connecting the crank end 15² of the trunnion 15¹ with the crank end 19¹⁰ of 10 the trunnion 19⁷.

30 indicate caster wheels journaled in the brackets 19 extending from each side of the rear end of the main frame and adapted to resiliently support the same, the shanks of 15 the fork bearings of the caster wheels being provided with cushioning springs 31. 32 indicates a portion of the deck of the binder. The main frame 1 is suitably connected to the main frame of the binder by 20 any desired means so that the binder and my stoker travel in unison.

Having described the principal parts involved in my invention I will briefly describe the operation of the same.

25 As the sheaves are ejected from the binder they are thrown on to the spicular projections 12^x of the plate 12. The plate 12 then supports the weight of the sheaf and is thereby depressed, the tension spring 12² and 30 the resilience of the rod 11 allowing for the depression. By the depression of the plate 12 the forward end of the rod 11 is sprung downward so that the downwardly projecting end 11⁰ thereof engages with the chain 35 3⁵. It will, of course, be understood that the sprocket wheel 2' revolves continuously, being mounted upon the shaft 2 which is driven through the gears 2^x and 2⁰ and sprocket 3¹⁰ and sprocket chain 3² from the 40 sprocket 3' carried by the shaft 3^x of the main carrier wheel 3. As the downward projection 11⁰ engages the chain 3⁵ the chain traveling in the direction of arrow (see Fig. 2) the rod 11 is moved longitudinally 45 compressing the spring 11' and sprocket 4^x slightly turning the sprocket so that the mutilated portion thereof is carried past the pinion 3⁴ allowing the pinion to engage with the teeth of the sprocket. As the pinion 3⁴ 50 engages with the teeth of the sprocket 4^x a driving connection is formed from the revolving sprocket 2' to the sprocket 4^x which in revolving draws the link 9 downward, throwing the sheaf receiver 8 into an upwardly tilted position so as to throw the sheaf forward therefrom to the shock former, which is, of course, in the open position shown in Fig. 1. During this operation the sprocket gear 4^x revolves until the 55 60 sprocket pinion again enters the mutilated portion thereby breaking the driving connection. This operation is repeated until the required number of sheaves have been received by the shock former.

65 The operator of the binder then pulls the

cord 15⁰ so as to throw the clutch members 2⁴ and 2³ into engagement thereby forming a driving connection between the shaft 2 and sprocket 2². By this means the sprocket 26, shaft 24 and crank wheel 27 are rotated. 70 The rotation of the sprocket 26 pulls the link 27 which is connected to the rear bar of the rocking frame 15 so as to rock the frame 15 upwardly into the dotted position shown in Fig. 2. Simultaneously the crank wheel 75 27⁰ pulls upon the link 28 connected to the crank arm 17² which rocks the frame 17 also into the dotted position shown in Fig. 2, carrying the shock former upwardly toward the dotted position. As the shock former 80 is carried upward the tension exerted on the cord 18' and looped cord 15⁸ pulls the arms 15⁷ of the levers 15³ relatively downward toward the dotted position and thereby forcing the opposite end 15³ of the lever 15 in 85 such a direction as to force the links 14⁵ inward, swinging the hinged portions 14² and 14³ of the shock former together so as to compress the shock.

It will, of course, be understood, that the 90 sheaves are so thrown into the former that the butt ends are at the wider end of the former and the heads at the narrow end so that when the portions 14² and 14³ of the shock former are forced together they 95 compress the shock in such a way as to draw the heads of the sheaves together and spread the butt ends so as to form a wide base for the shock to rest on when upended upon the ground. As the shock former is upended 100 into the dotted position the frame 19⁵ is swung outward so as to allow for clearance to enable the former to assume the dotted or upended position. This is accomplished by means of the link connection 29 between the 105 crank arms 15² and 19¹⁰.

It will thus be seen that when the rocking frame 15 is swung into the dotted position the swinging frame 19⁵ will be swung outward also into the dotted position.

As the sprocket wheel 26 and crank wheel 27 complete their revolution they carry the link connections 27 and 28 back to their normal position thereby carrying the swinging frames 15 and 17 from their dotted position back to their normal position or the position shown in full lines in the drawing and thereby returning the shock former to its normal position. As it is returned the levers 15³ are carried back to the position shown 115 in full lines, the springs 14⁴ aiding to swing the members 14² and 14³ of the shock former outward to the open position ready to receive the next set of sheaves.

From this description it will be seen that 125 I have devised a very simple device whereby the sheaves delivered from the binder may be formed into a shock and delivered and set up in the upstanding position upon the ground.

What I claim as my invention is:

1. In a stooker, the combination with the main frame and shock former comprising a semi-cylindrical lower portion and arc-shape flaps forming the upper portion, of means for carrying the shock former upon the main frame and adapted to be swung to carry the former toward an upended position, levers pivoted upon the lower portion of the former, a link connection between one end of each lever and the corresponding former flap, and means drawing upon the opposite end of each lever as the former is carried upward to turn the levers upon their pivot to close the flaps.
2. In a stooker, the combination with the main frame, of a conical shock former, a pair of crank arms pivotally mounted in the frame one in advance of the other, a bearing carried by the shock former in which the rear crank is journaled, a link rod connecting the forward crank and the corresponding end of the shock former, and means for swinging the cranks upward to carry the former into position to allow the shock to drop.
3. In a stooker, the combination with the main frame and conical shock former comprising a semi-cylindrical lower portion and arc-shape flaps forming the upper portion, of means for carrying the shock former upon the main frame and adapted to be swung to carry the former toward an upended position, levers swung upon the lower portion of the former, a link connection between one end of each lever and the corresponding former flap, a pulley mounted in the main frame, a cord extending beneath the pulley and having a bifurcated portion at one end connected to each forward end of the levers carried by the shock former, and a tension spring connecting the opposite end of the cord with the main frame.
4. In a stooker, the combination with the main frame, a shock former mechanism adapted to swing for upending the shock former in the main frame, a swinging closure for the rear end of the shock former, means for locking the closure against the open rear end of the shock former, means for releasing such locking means operated by the upward swing of the former carrying mechanism, and means for swinging the closure clear of the shock former as the shock former is swung to an upended position.
5. In a stooker, the combination with the main frame and carrying wheels thereof, of a mutilated gear mounted upon the main frame, a pinion also mounted in the main frame and adapted to engage with the mutilated gear, means for driving the pinion

from one of the carrying wheels of the main frame, a tilttable plate forming the sheaf receiver, a link connection between one end of the plate and the mutilated gear, and means set into operation by the weight of the sheaf received upon the receiver for turning the mutilated gear to carry the teeth thereof into engagement with the pinion.

6. In a stooker, the combination with the main frame and carrying wheels thereof, a pinion mounted upon a shaft carried by the main frame, a sprocket drive between the carrying wheels and the pinion, a mutilated gear, a tiltably mounted sheaf receiving plate carried by the main frame, a link connection between one end of the plate and the mutilated gear, and a trip device operated by the weight of the sheaf to engage the sprocket drive and the teeth of the mutilated gear whereby movement is imparted to the mutilated gear to carry the teeth thereof into engagement with the pinion.

7. In a stooker, the combination with the main frame and carrying wheels thereof, a pinion carried by the shaft journaled in the main frame, a sprocket drive between the pinion and the carrying wheel, a mutilated gear mounted upon a shaft also carried by the main frame, a tilttable sheaf receiving plate, a link connection between the sheaf receiving plate and the mutilated gear, a longitudinally movable resiliently held rod having means at one end adapted to engage the sprocket drive and at the opposite end to engage the teeth of the mutilated gear, and means operated by the weight of the sheaf received upon the sheaf receiver for carrying one end of the rod into engagement with the chain of the sprocket drive.

8. In a stooker, the combination with the main frame and carrying wheels thereof, a pinion carried by the shaft journaled in the main frame, a sprocket drive between the pinion and the carrying wheel, a mutilated gear mounted upon a shaft also carried by the main frame, a tilttable sheaf receiving plate, a link connection between the sheaf receiving plate and the mutilated gear, a longitudinally movable resiliently held rod having means at one end adapted to engage the sprocket drive and at the opposite end to engage the teeth of the mutilated gear, a supplemental plate located above the sheaf receiving plate and resiliently supported at one end, and a link connection between the opposite end of the plate and the longitudinally movable rod.
